UNITED STATES PATENT OFFICE.

FRED H. L. LUEBBE, OF PHILADELPHIA, PENNSYLVANIA.

DESIGN FOR HOSIERY.

Application filed December 16, 1927 Serial No. 24,506. Term of patent 14 years.

To all whom it may concern:

Be it known that I, FRED H. L. LUEBBE, a citizen of the United States, residing at Philadelphia, in the county of Philadelphia and State of Pennsylvania, have invented a new, original, and ornamental Design for Hosiery, of which the following is a specification, reference being had to the accompanying drawing, forming part thereof.

I claim:

The ornamental design for hosiery as shown.

FRED H. L. LUEBBE.
